CLAIM

The ornamental design for a divider panel for food storage container, as shown and described.

DESCRIPTION

FIG. 1 is a perspective view of a divider panel for food storage container, showing my new design, shown in an exploded position of use with an exemplary food storage container;

FIG. 2 is a front elevational view thereof, shown with the exemplary food storage container removed to show aspects of the design not visible when combined;

FIG. 3 is a rear elevational view thereof;

FIG. 4 is a left side elevational view thereof;

FIG. 5 is a right side elevational view thereof;

FIG. 6 is a top plan view thereof; and;

FIG. 7 is a bottom plan view thereof.

The broken line showing of a food storage container is included for the purpose of illustrating environmental structure and forms no part of the claimed design.
